CLAIM

We claim the ornamental design for the collapsible over the sink colander, as shown and described.

DESCRIPTION

FIG. 1 is a top perspective view of the collapsible over the sink colander, showing our new design.

FIG. 2 is a front view of the collapsible over the sink colander, the back view being a mirror image.

FIG. 3 is a top view of the collapsible over the sink colander.

FIG. 4 is a right side view of the collapsible over the sink colander.

FIG. 5 is a left side view of the collapsible over the sink colander; and,

FIG. 6 is a bottom view of the collapsible over the sink colander.

Features illustrated in broken lines show an intended environment for the collapsible over the sink colander and form no part of the claimed invention.
